(57) **CLAIM**

The ornamental design for a golf putter, as shown and described.

DESCRIPTION

FIG. 1 is an isometric view of a golf putter;
FIG. 2 is a top view of a golf putter;
FIG. 3 is a front view of a golf putter;
FIG. 4 is a right side view of a golf putter;
FIG. 5 is a rear view of a golf putter;
FIG. 6 is a bottom view of a golf putter; and,
FIG. 7 is a bottom perspective view of a golf putter.
The broken line showing of the shaft is for illustrative purposes only and forms no part of the claimed design.

1 Claim, 2 Drawing Sheets
